GARMENT CLEANING MACHINE

Jean Louis Boulade, Alturas, Calif.

Application February 8, 1946, Serial No. 646,439

3 Claims. (Cl. 68—23)

1

This invention relates in general to improved machinery for use in laundries or dry cleaning establishments.

One object of the present invention is to provide a garment cleaning machine adapted for either washing or dry cleaning of garments by forcing a cleaning liquid through the garments by centrifugal force; the garments being disposed in rotary baskets of novel design, and said baskets—for the cleaning operation—running submerged in a quantity of cleaning liquid in a tub.

Another object of the invention is to provide a garment cleaning machine, as in the preceding paragraph, in which the rotary baskets are mounted for manually controlled, vertical movement from said submerged position to an elevated position above the surface of the cleaning liquid in the tub; the baskets being power driven in either position, and when elevated function to extract the cleaning liquid from the garments by centrifugal force. Thus, cleaning and extraction are accomplished in the same machine without the necessity of draining the same; the machine being economical in operation, as it functions with a relatively small quantity of the cleaning liquid and a minimum of operational loss thereof.

Additional objects of the invention are to provide a garment cleaning machine arranged for ease of loading and unloading the garments; to provide a machine which functions rapidly and smoothly to produce proper cleaning of garments; to provide a machine which can clean garments—such as wool—without injury thereto; and to provide a machine which is practical, durable, and exceedingly effective for the purpose for which it is designed.

These objects are accomplished by means of such structure and relative arrangement of parts, as will fully appear by a perusal of the following specification and claims.

In the drawings:

Fig. 1 is a sectional elevation of the machine.

Fig. 2 is an enlarged, fragmentary transverse sectional elevation, showing mainly the mounting of the sliding glass top on the tub.

Fig. 3 is a plan view of the machine.

Fig. 4 is a sectional plan view of one of the rotary baskets.

Fig. 5 is an enlarged fragmentary elevation, partly in section, showing mainly the means for raising one basket on the corresponding splined drive shaft.

Fig. 6 is a cross-section on line 6—6 of Fig. 5.

2

Referring now more particularly to the characters of reference on the drawings, the improved garment cleaning machine comprises an upstanding rectangular tub 1 of substantial height, said tub being supported by a base 2 which includes corner legs 3. The tub is formed with a bottom 4 which inclines downwardly to the center, and a drain pipe 5 leads from said center of the bottom to a suitable point of discharge. A shut-off valve 6 is interposed in the drain pipe 5, and a valve control rod 7 extends laterally from beneath the tub to a point of access adjacent one end of the latter.

The tub is fitted, on top, with a relatively narrow, longitudinally extending center plate 8 disposed approximately midway between opposite sides of the tub 1. To the back of the center plate 8 the tub includes a closed top 9, but in front of said center plate the tub is normally covered by a movable glass top 10; said movable glass top being mounted for sliding movement forwardly from its horizontal tub closing position, as shown in Figs. 2 and 3, to a downwardly depending position in front of the tub, as shown by dotted lines in Fig. 2. The glass top 10, which is suitably framed, as shown, is mounted for the above movement by means of laterally projecting trunnions 11 on the inner corners of said top, which trunnions ride in guide channels 12 on the upper edges of the tub; said guides extending forwardly from adjacent the center plate 8 to the front edge of the tub and then curving downwardly a short distance. With the trunnions 11 carried in the guides 12, movement of the glass top 10 from its horizontal tub closing position to its depending position in front of the tub can be accomplished. The glass top 10 is fitted, at its forward edge, with suitable handles 13.

A pair of vertical drive shafts 14 are mounted in the tub in spaced relation, said shafts being journaled in connection with the bottom 4 of the tub by bearings 15, and being journaled in connection with the center plate 8 by top bearings 16.

The vertical drive shafts 14 extend upwardly to a termination some distance above the top bearings 16, and above the latter are fitted with pulleys 17 connected by an endless crossed belt 18.

An electric motor 19 is mounted on one end of the tub, with the motor shaft 20 projecting upwardly. An endless belt and pulley unit 21 connects the motor shaft 20 and the adjacent drive shaft 14. By reason of the above arrangement

the shafts 14 are simultaneously driven by the motor 19, but in reverse directions.

Within the tub 1 each vertical drive shaft 14 is surrounded by a circular, rotary basket indicated generally at 22. As these baskets are of identical construction a description of one will suffice for both. Each basket 22 includes a perforate bottom 23, and a perforate top, the latter comprising a pair of semi-circular covers 24 hinged, as at 25, along adjacent edges, substantially diametrically of the basket, for upward opening movement. The semi-circular covers 24 are each normally held against opening by a manually releasable catch 26. Between the top and bottom thereof each basket is formed with a plurality of segmental compartments 27, each being formed by a pair of relatively widely spaced radial partitions 28, and a circumferential outer wall section 29. Adjacent ones of the radial partitions 28 of the different segmental compartments are spaced apart circumferentially of the basket a short distance so as to form relatively narrow segmental channels 30 open at their outer ends to the periphery of the basket. The radial partitions 28, together with the circumferential outer wall sections 29, are perforate, as shown.

The baskets 22, for the cleaning operation, are disposed in the tub 1 adjacent the bottom thereof and below the surface 31 of a quantity of cleaning liquid in the tub which substantially half fills the same. The baskets 22 are driven by the vertical shafts 14 as follows:

Within the tub 1 the vertical drive shafts 14 are splined, as at 32, and the baskets include bottom hubs 33 and top hubs 34 slidably secured in matching relation on the splines 32. Protective sleeves 35 extend between the bottom hub 33 and top hub 34 of each basket in surrounding relation to the corresponding spline 32. By reason of the above arrangement it will be seen that when the shafts 14 and splines 32 are driven—in reverse directions—the baskets are correspondingly rotated.

The baskets 22 are vertically movable on the splines 32, from a submerged position below the surface 31 of the cleaning liquid, as shown in full lines in Fig. 1, to an elevated position above said liquid, as shown in dotted lines in said figure, by means of the following mechanism:

The splines 32 are longitudinally slotted on opposite sides, as at 36, and the shafts 14 are hollow from end to end thereof. Lift rods 37 slidably engage in the shafts 14 from their upper ends. At its lower end each lift rod 37 is fitted with a cross bar 38 which projects through the opposed slots 36 and engages beneath the top hub 34 of the corresponding basket. At their upper ends the lift rods 37 each include a hand loop 39. By pulling upward on the lift rods 37 by the hand loops 39, the top hubs 34 of the baskets are engaged and lifted, resulting in raising of said baskets on the splines 32 to said above-liquid position. The lift rods 37 are locked in elevated position by any suitable means, such as removable cross pins 40 which engage through transverse openings in said rods and seat in matching notches in the upper ends of the corresponding drive shafts 14, as clearly shown in Fig. 5.

When the above described garment cleaning machine is in use, the garments are placed in the segmental compartments 27 of the baskets and the latter disposed in their lowered position in the tub 1, wherein said baskets are submerged in the cleaning liquid. The drive motor 19 is then

started, which causes the baskets 22 to reversely rotate at substantial speed.

By reason of the particular compartmentation of the baskets 22 the garments cannot pack together at one point in the circumference of the baskets, and are maintained in spaced relation for proper cleaning; i. e., for effective flow of the cleaning liquid through said garments. The relatively thin segmental channels 20 which exist between adjacent sides of the segmental compartments 27 assure of proper flow of the cleaning liquid into and out of said compartments 27. After the baskets 22 run in the cleaning liquid for a predetermined length of time, and during which time the cleaning liquid has been constantly urged through the garments by centrifugal force, the rotation of the baskets is then temporarily discontinued and said baskets are then elevated to their above liquid position, as shown in dotted lines in Fig. 1. Rotation of the baskets is then again commenced and during such rotation the cleaning liquid remaining in the garments is effectively discharged therefrom by centrifugal force, and is thus delivered back into the tub. When the garments have had substantially all of the cleaning liquid extracted therefrom by the above rotary motion of the baskets 22, the drive for the same is stopped and the movable glass top 10 is shifted to its open position, which exposes certain of the semi-circular covers 24 for opening, so that the cleaned garments may be readily removed from the baskets. Further garments are then placed in the baskets 22 and the above described operation is repeated, after removal of the cross pins 40 and lowering of the baskets to their submerged working position.

From the foregoing description it will be readily seen that there has been produced such a device as substantially fulfills the objects of the invention as set forth herein.

While this specification sets forth in detail the present and preferred construction of the device, still in practice such deviations therefrom may be resorted to as do not form a departure from the spirit of the invention, defined in the appended claims.

Having thus described the invention, the following is claimed as new and useful and upon which Letters Patent are desired:

50. 1. A garment cleaning machine comprising a tub of substantial depth, a hollow vertical shaft having a splined portion extending into the tub, power means arranged to drive the shaft, a perforate, rotary basket surrounding the shaft in the tub, the basket including a hub splined on the splined portion of the shaft for vertical adjustment of said basket between a lowered and a raised position in the tub, and means operative to adjust the basket between said positions; said 55 adjusting means comprising a lift rod slidably mounted in the hollow shaft, a cross head on the lower end of the rod, the splined portion of the shaft in the tub being vertically slotted on opposite sides and the ends of the cross head projecting therethrough and engageable with the hub from below, and means to releasably secure the lift rod at an elevated point whereby to maintain the basket in its corresponding position.
60. 2. A garment cleaning machine comprising a tub of substantial depth, a hollow vertical shaft having a splined portion extending into the tub, power means arranged to drive the shaft, a perforate, rotary basket surrounding the shaft in the tub, the basket including a hub splined on the
65. 3. A garment cleaning machine comprising a tub of substantial depth, a hollow vertical shaft having a splined portion extending into the tub, power means arranged to drive the shaft, a perforate, rotary basket surrounding the shaft in the tub, the basket including a hub splined on the
70. 4. A garment cleaning machine comprising a tub of substantial depth, a hollow vertical shaft having a splined portion extending into the tub, power means arranged to drive the shaft, a perforate, rotary basket surrounding the shaft in the tub, the basket including a hub splined on the
75. 5. A garment cleaning machine comprising a tub of substantial depth, a hollow vertical shaft having a splined portion extending into the tub, power means arranged to drive the shaft, a perforate, rotary basket surrounding the shaft in the tub, the basket including a hub splined on the

splined portion of the shaft for vertical adjustment of said basket between a lowered and a raised position in the tub, and means operative to adjust the basket between said positions; said adjusting means comprising a lift rod slidably mounted in the hollow shaft, a cross head on the lower end of the rod, the splined portion of the shaft in the tub being vertically slotted on opposite sides and the ends of the cross head projecting therethrough and engageable with the hub from below, the rod having a transverse opening therethrough disposed at the upper end of the shaft when the rod is raised to elevate the basket, and a cross pin adapted to then releasably engage through the transverse opening and rest on said end of the shaft.

3. A garment cleaning machine comprising a tub of substantial depth, a hollow vertical shaft having a splined portion extending into the tub, power means arranged to drive the shaft, a perforate rotary basket surrounding the shaft in the tub, the basket including two vertically spaced-apart hubs, at least one of which hubs is splined on the splined portion of the shaft for vertical adjustment of said basket between a lowered and a raised position in the tub, and means operative to adjust the basket between said positions, such latter means comprising a lift rod

slidably mounted in the hollow shaft, a cross-head on the lower end of the rod, the splined portion of the shaft being vertically slotted on opposite sides of the shaft, the crosshead projecting in guided relation into said slots between the hubs and being engageable with the upper hub, whereby upon vertical movement of the rod the basket may be raised or lowered, means to releasably secure the rod at an elevated point, and a sleeve connected between the hubs and surrounding the shaft.
